CLAIM

The ornamental design for a display screen portion with icon, as shown and described.

DESCRIPTION

The present application is also related to U.S. Design patent application Ser. No. 29/623,813, U.S. Design patent application Ser. No. 29/623,844, U.S. Design patent application Ser. No. 29/623,820, U.S. Design patent application Ser. No. 29/623,826, and U.S. Design patent application Ser. No. 29/623,833, filed Oct. 27, 2017, the entire disclosures of which are incorporated herein by reference.

FIG. 1 is a front view of a display screen portion with icon according to our design;

FIG. 2 is a second image thereof

FIG. 3 is a third image thereof

FIG. 4 is a fourth image thereof;

FIG. 5 is a fifth image thereof;

FIG. 6 is a sixth image thereof;

FIG. 7 is a seventh image thereof;

FIG. 8 is an eighth image thereof; and,

FIG. 9 is a ninth image thereof.

The dash-dot broken lines showing the display screen portion depict the bounds of the claimed design and form no part thereof. In the figures, the perimeters of the portion of the underlying display screen and the graphical interface illustrating the icon are understood to be flush.

Shading depicts a contrast in appearance.

The appearance of the image sequentially transitions between FIGS. 1-9. The process or period in which one image transitions to another image forms no part of the claimed design.
